HANDLE FOR PNEUMATIC TOOLS

Filed Nov. 24, 1926

INVENTOR.
Francis A. Jimerson
BY *Herbert G. Odeur*
HIS ATTORNEY

UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

HANDLE FOR PNEUMATIC TOOLS.

Application filed November 24, 1926. Serial No. 150,495.

This invention relates to percussive tools but more particularly to a device for securing of handle and back head to the tool cylinder.

5 One object of this invention is to enable the back head of the tool to be held securely in place with respect to the cylinder during the operation of the tool.

Further objects will be in part obvious 10 and in part pointed out hereinafter.

The invention consists of the features of construction and the combination of elements substantially as hereinafter described and more particularly pointed out in the 15 appended claim and illustrated in the accompanying drawing, in which—

Figure 1 is a longitudinal partial sectional elevation of a pneumatic hammer tool constructed in accordance with the practice of 20 the invention,

Figure 2 is a plan view in section taken on the line 2—2 of Fig. 1 looking in the direction of the arrows, and

Figure 3 is a perspective view of one of 25 the bolts used to secure the back head and handle to the cylinder.

Referring to the drawing, A is the cylinder of a pneumatic hammer tool having a back head B and a handle portion C. The 30 cylinder A is provided with a reciprocating hammer piston D by means of which blows of impact are delivered to the drill steel or tool (not shown). A handle E is provided with a throttle lever F which controls the admission of motive fluid to a passage G.

In the back head B, a valve chamber H is formed housing a reciprocating valve J. A passage K leads from the valve chamber H to conduct pressure fluid to the front end 40 of the cylinder A and a passage L conducts pressure fluid to the rear end of the cylinder A. Intermediate the front and rear ends of the cylinder A an exhaust port O leads to the atmosphere and the port P is located intermediate the exhaust port O and the rear end of the cylinder A.

A raised cylindrical portion Q is provided

on the front face of the back head B fitting closely into the rear end of the cylinder bore A'.

50 A pair of lugs R are formed on the front end of the handle portion C and bolts S having a threaded portion T at one end and a hooked end U are provided to secure the handle portion C, the back head B, and the cylinder A in a fixed relative position.

55 A preferred construction of the bolts S is shown in the drawing in which flat faces V and W of the bolt lie against corresponding flat spots V' and W' on the cylinder A. Hooked portions X are formed on the cylinder A in the recesses Y. These hooked portions are similar to the hooked ends U of the bolts S.

60 In assembling the tool the back head B is so placed that the raised cylindrical portion Q fits the cylinder bore A'. The bolts S are then placed so that the hooks U engage the hooks X on the cylinder A and are held in place by hand until the portion C 70 is brought into position and the bolts S passed through the lugs R. Lock washers Z are then placed over the ends of the bolts S and the nuts b screwed firmly into place thus securing the handle C, back head B and 75 cylinder A rigidly in position relative to each other.

75 I claim:

In a pneumatic tool, the combination of a 80 cylinder, a back head forming a closure for the cylinder, a handle portion, lugs on said handle portion, bolts passing through said lugs, said bolts having screw threads for the reception of nuts on the rear end, flat faces on the front end, hooked portions on 85 the front end, similar flat faces and hooked portions formed on and in the cylinder wall permitting cooperation between the bolts and the cylinder whereby the back head and cylinder are secured rigidly relative to each 90 other.

In testimony whereof I have signed this specification.

FRANCIS A. JIMERSON.
